GARMENT HANGER FORMING MACHINE

John H. Moore, Detroit, Mich., assignor, by mesne assignments, to Andrew Ruen Hanger Co. Inc., a corporation of Michigan

Application February 29, 1932, Serial No. 595,692

20 Claims. (Cl. 140—71)

My invention relates to a new and useful improvement in a garment hanger forming machine and particularly the twisting mechanism used therewith, the mechanism for engaging the wire 5 in the twisting mechanism, the particular structure of the mechanism and the operation thereof, and an aligning mechanism for maintaining the wires in alignment prior to the twisting operation. This application forms in part a continuation of an improvement on the structure illustrated in my co-pending application, Serial No. 432,322, now issued as Patent No. 1,888,803 dated November 22, 1932.

It is an object of the present invention to provide in a forming machine of this class a twisting mechanism whereby the strands of wire to be twisted will be maintained in alignment so that their entry into the twisting mechanism will be facilitated and so that they will be maintained in proper position for a twisting operation.

It is another object of the present invention to provide a twisting mechanism whereby an easy and quick release of the twisted strands of wires therefrom may be effected.

It is another object of the present invention to provide in a forming machine of this class a mechanism whereby the overlapping ends of a strand of wire may be moved into alignment and securely clamped together.

Another object of the invention is the provision in a forming machine of this class of a twisting mechanism embodying movable wire-engaging dies normally out of center of the rotating member and movable to a position for retaining the wire strands in the center during the twisting operation and movable out of the center for releasing the wire strands subsequent to the twisting operation.

It is another object of the invention in a forming machine of this class to provide a twisting and aligning mechanism which lends itself to operation by stationary cams around which cam actuated members may be caused to travel.

Other objects will appear hereinafter.

45 The invention consists in the combination and arrangement of parts hereinafter described and claimed.

The invention will be best understood by reference to the accompanying drawings which form a part of this specification, and in which,

Fig. 1 is an elevational view of a forming machine embodying the invention.

Fig. 2 is a fragmentary sectional view taken on 55 line 2—2 of Fig. 1.

Fig. 3 is a sectional view taken on line 3—3 of Fig. 1.

Fig. 4 is a sectional view taken on line 4—4 of Fig. 2.

Fig. 5 is a sectional view taken on line 5—5 of Fig. 4.

Fig. 6 is a view similar to view 5 of the operation of the mechanism in a prior position of operation with parts broken away.

Fig. 7 is a sectional view taken on line 7—7 of Fig. 4.

Fig. 8 is a fragmentary and large sectional view of a portion of the mechanism illustrated in Fig. 3.

Fig. 9 is a sectional view taken on line 9—9 of Fig. 8.

Fig. 10 is a fragmentary sectional view taken on line 10—10 of Fig. 2.

Fig. 11 is a view taken on line 11—11 of Fig. 1.

The structures with which the invention is used comprise a base 20 projecting upwardly from which are standards 18, 19 and 98 which serve to support a hopper 110 shown in dotted lines in Fig. 1. A drum 104 is rotatably mounted on the standards 19 and 98.

A pulley 16 is provided which may be connected by a belt to a suitable source of power. This pulley 16 is fixedly mounted on the shaft 17 which is journaled in the standards 18 and 19. A pinion 21 is fixedly mounted on the shaft 17 and meshes with and serves to drive the gear 22 which serves to drive the pinion 23 through the clutch 24 operated by the rockable yoke 25. The pinion 23 is in mesh with a gear 26. This gear 26 meshes with the pinion 27 which is fixedly mounted in the shaft 28. This pinion 27 and the shaft 28 are not operative for actuating the mechanism which forms the subject matter of this application, but serve another purpose and particularly the feeding mechanism for feeding the wire from the hopper 110. The gear 26 is fixedly mounted on the stub 29 which projects outwardly from the head 30 carried by the end wall of the rotatable drum 104 so that by a rotation of the gear 26 the drum 104 is rotated.

Positioned on beds 111 about the rotatable drum 104 are sets of forming mechanism each set being complete in itself so that in the rotation of the drum, each of the mechanisms which is complete in itself will pass through a complete cycle of operation and in Fig. 2 a portion of two sets of mechanisms have been illustrated, the beds 111 rotating from left to right about the axis of the drum 67.

Embracing the head 30 is a bushing 31 on which is mounted by a press fit, a cam drum 32 110

- attached to the standard 19 and having a cam groove 33 formed in its periphery and in which engages the stud 34 projecting radially outwardly from the push shaft 35 which is slidable in the bearing 36 mounted in the drum end wall 104 and keyed therein by the key 37 against rotation. A connection 38 serves to connect the rock shaft 35 pivotally to one end 39, the other end of which is pivotally connected to the housing 40 in which is positioned the gear 42 mounted fixedly on the shaft 43, this gear 42 meshing with the twister gear 41 as clearly appears in the Fig. 2. A bushing 44 is pressed into the housing 40 to serve as a bearing for the shaft 43.
- 15 The strand of wire 46 when fitted onto the forming mechanism of the drum 104 engages on a slot 45 formed in the forming blocks 47 and in a proper position of the drum 104 in its rotation the ends of the wire are whipped inwardly by the arms 48.
- 20 Mounted on the bed 111 is a block 49 cut away as at 50 to provide space for reception of the clamping discs 53 and 54. The disc 54 is fixedly mounted on the shaft 52 which is a driven shaft, and the disc 53 is fixedly mounted on the shaft 52' which is not a driven shaft, these shafts projecting through a block 49. The shaft 52 is provided with a reduced portion 51. Teeth 55 and 56 are formed on the periphery of the discs 53 and 54 respectively, but only for a portion of the circumference intermeshed as shown in Fig. 5. Each of the discs is cut away as at 57' but the cut away portion is left at one end to provide an upstanding clamp lug 57. Guide strips 112 and 113 are provided so that when the ends of the wire are whipped inwardly by the arms 48 the ends of the wire riding over the guide strips 112 and 113 are snapped into position behind the clamp lugs 57 and rest upon the face of the discs 53 and 54. The reduced portion 51 of the shaft 52 and the similarly reduced portion of the shaft 52' projects through the abutment formers 58, each of which is cut away as at 59 (see Fig. 7) against which the wire ends are forced by the lugs 57 when the discs 53 and 54 are rotated so that the wire is brought from the position shown in Fig. 6 to the position shown in Fig. 5 and in Fig. 7. An adjusting screw 109 is threaded into the block 49 so that the abutment discs 58 may be rocked on their pivot so as to vary in contour or shape given to the wire when the same is clamped against the abutment discs by the lugs 57.
- 25 The shaft 52 is locked by means of the pinion 60 which is fixedly mounted thereon and with which meshes the teeth formed on the end of the segment bearing 61 which is rockably mounted on the sleeve 63 which is swingably positioned on the shaft 62. Projecting from the sleeve 63 is the arm 64 carrying the stud 65 which engages in the cam groove 66 formed in the periphery of the stationary drum 67 supported by the shaft 105 projecting from one end thereof and engaging in a bushing 106 pressed into a socket 106' formed in the head 30. A shaft 107 projects from the opposite end of the drum 67 and is journaled in a bushing 107'. A pin 107" serves to key the shaft 107 to the head 115 which is fixedly mounted on the standard 98. The arm 61 is provided with a slot 116 in which engages the boss 117 projecting from one face of the arm 64 adjusting screws 118 and 119 and threaded inwardly of the slot 116 (see Fig. 2 and Fig. 10) to adjust the relative position of the arm 61 and the boss 117. This construction is such that as the drum 104 rotates so as to carry the stud 65

around the drum 67 the arm 64 will be rocked which will cause a rocking of the arm 61 and consequently through the pinion 60 a rocking of the arm 52.

Prior to the sinking inwardly of the arms 48 the arm 70 will be in the position shown in full lines shown in Fig. 1. A neck 69 mounted on the end of the arm 70 is provided with an outwardly projecting pin 68 having at its opposite sides the wire receiving groove 120 (see Fig. 2 and Fig. 3). As the ends of the wire 46 are whipped inwardly by the arms 48 they will end close to each other and engage the pin 68 so as to lie in the groove 120. This arm 70 is fixedly mounted on the shaft 71 (see Fig. 1 and Fig. 3). A lateral arm 72 fixedly mounted on the end of the arm 71 carries a pin or stud 73 which engages in the cam groove 74 formed in the stationary drum 67.

The twister gear 41 which meshes with the gear 42 is provided with a radially extended slot 75 extending outwardly from slightly beyond its center. A cover 76 which is secured over one face of the gear 41 (see Fig. 9) is provided with a slot 75'. The covered face of the gear 41 is cut away as at 77 to provide at diametrically opposite sides 100 the semi-cylindrical bosses 78 and 79 against which engage the concave faces of the arcuate die shoes 80 and 81, the convex of which engage against the projection 85 formed in the gear 41 by the milling away referred to. Springs 82 and 105 83 are positioned behind and engaged in a socket formed in the die shoes 80 and 81 so as to normally maintain the recess 121 formed in the convex surface of each of the die shoes 80 and 81 thrust outwardly beyond the center of the member 41. It will be noted that these recesses 121 are of such shape and size that two strands of wire may be positioned therein side by side and closely locked together when the die shoes are moved into center position as shown in full lines 115 in Fig. 8.

The shaft 43 is connected by the coupling 86 to the shaft 87 which is journaled in the bearing 88 and on which is fixedly mounted the bevel gear 87' therein. This bevel gear 87' meshes 120 with the bevel gear 89 fixedly mounted on the shaft 91 which is journaled in the bearing 90 and which is connected with the coupling 92 to the shaft 93 on which is fixedly mounted the gear 94. A radially projected arm 95 is also fixedly 125 mounted on the shaft 93 carrying an outwardly projecting roller 96 which is adapted to ride on the cam plate 99 mounted on the inner face of the standard 98. Projecting over the cam plate 99 is a guide bearing 97 so that as the rotatable drum 104 rotates to carry the roller 96, the guide bearing 97 the roller 96 will be pressed tightly against the surface 99. A bracket 101 is fixedly mounted on the standard 98 carrying the segment plate 102 with which the teeth of the gear 94 may engage so that at predetermined positions of the drum 104 the shaft 91 will be rotated. As the gear 94 rides off of the segment 102 the roller 96 will engage the guide bearing 103 which will return it to its normal or neutral position in engagement with the surface 99. In operation when the gear 26 is rotated the drum will be rotated carrying with it the forming mechanism mounted thereon and in the proper position of the drum 104 relatively to the hopper 110 the strand 145 of wire 46 will be deposited in the slots 45 and securely clamped in position as the rotation continues, the proper cam actuation will be effected to swing the arm 48 inwardly to the position shown in Fig. 1. As these arms swing inwardly 150

the arm 70 will be in the position shown in Fig. 1 and the ends of the wire will ride over the guide members 112 and 113 to engage behind the lugs 57 and against the surface 59 and again 5 rock the housing 40 to its original position and as the member 41 is carried away from the location of the twisted ends of the wire, the die shoes 80 and 81 will move forwardly until they pass the center of the member 41 into open position 10 as shown in the dotted lines in Fig. 8. This is an important feature of the invention inasmuch as, through the twisting operation, the ends of the wire are placed under circumferential strain resulting from the torque strain transmitted to 15 the wire and the back lash resulting therefrom. These ends which are engaged by the die shoes are also subject to a strain longitudinally of their length and by having the die shoes open to release the ends of the wire a binding or clamping 20 of the twisted ends within the die is eliminated and an easy and quick release of the same therefrom effected.

While I have illustrated and described the preferred form of construction, I do not wish to limit 25 myself to the precise details of structure shown but desire to avail myself of such variations and modifications as come within the scope of the appended claims.

Having thus described my invention, what I 30 claim as new and desire to secure by Letters Patent is:

1. In a forming machine of the class described, a movable carrier movable in a cycle of operation; a wire engaging portion on said carrier; 35 a twisting mechanism on said carrier for twisting the wire in said wire receiving portion; cam actuated means for moving said twisting mechanism into wire engaging position and out of wire engaging position upon the movement of said carrier to predetermined positions.

2. In a forming machine of the class described, a movable carrier movable in a cycle of operation; a wire engaging portion on said carrier; a twisting mechanism on said carrier for twisting 45 the wire in said wire receiving portion; cam actuated means for moving said twisting mechanism into wire engaging position and out of wire engaging position upon the movement of said carrier to predetermined positions; and a cam actuated means for operating said twisting mechanism upon movement of the same to wire engaging position.

3. In a forming machine of the class described, a wire receiving member; abutment members; 50 means for engaging the wire adjacent its ends and bending the same into engagement with said abutment members, with the ends projecting radially therefrom; means for maintaining said ends in alignment; a twisting mechanism; means for moving said twisting mechanism into engagement with said aligning ends; and means operable upon movement of said twisting mechanism into said engagement for moving said alignment means out of engagement with said ends.

4. In a forming machine of the class described, a wire receiving member; abutment members; means for engaging the wire adjacent its ends and bending the same into engagement with said 55 abutment members, with the ends projecting radially therefrom; means for maintaining said ends in alignment; a twisting mechanism; means for moving said twisting mechanism into engagement with said aligning ends; means operable upon movement of said twisting mechanism into said engagement for moving said alignment means out 60

of engagement with said ends; and means for operating said mechanism for twisting said ends upon engagement of said twisting mechanism therewith.

5. In a forming machine of the class described, 65 a wire receiving portion; a twisting mechanism for twisting the ends of the wire; an aligning mechanism for aligning the ends of the wire; means for moving said twisting mechanism into engagement with the aligning ends; and means for moving said aligning mechanism out of engagement with said ends upon movement of said twisting mechanism into engagement with said ends.

6. In a forming machine of the class described, 70 a movable twisting mechanism for twisting strands of wire about each other; an aligning mechanism for aligning the strands of wire to be twisted; means for moving said aligning mechanism into operative and inoperative position; means for moving said twisting mechanism into operative and inoperative position, said moving means of said aligning mechanism and said moving means of said twisting mechanism operating in unison with each other for effecting a movement of said aligning mechanism into inoperative position upon movement of said twisting mechanism into operative position.

7. In a forming machine of the class described, 75 a movable twisting mechanism for twisting strands of wire about each other; an aligning mechanism for aligning the strands of wire to be twisted; means for moving said aligning mechanism into operative and inoperative position; means for moving said twisting mechanism into operative and inoperative position, said moving means of said aligning mechanism and said moving means of said twisting mechanism operating in unison with each other for effecting a movement of said aligning mechanism into inoperative position upon movement of said twisting mechanism into operative position; and means for actuating said twisting mechanism upon movement of the same to operative position.

8. In a forming machine of the class described, 80 a twisting mechanism comprising: a rotatable twisting member having a radially extending slot formed therein; a pair of oppositely disposed wire engaging dye shoes, movably mounted in said twisting member, and movable into position for clamping strands of wire in said twisting mechanism during the operation thereof, and movable into position for releasing said strands of wire upon completion of the twisting operation.

9. In a forming machine of the class described, 85 a twisting mechanism comprising: a rotatable twisting element having a radially extending slot formed therein for reception of aligned strands of wire; a pair of movable oppositely disposed dye shoes carried by said twisting element, and movable inwardly and outwardly relatively to the center of said twisting element, and adapted upon movement inwardly to a predetermined position for clamping the strands of wire at the center of said twisting element, and adapted, upon movement outwardly from said center, for releasing said strands of wire.

10. In a forming machine of the class described, 90 a twisting mechanism comprising: a twisting element having a radially disposed slot projecting outwardly from the center thereof; a pair of oppositely disposed movable dye shoes carried by said element having on the oppositely disposed faces a recess, said shoes being movable into position for clamping strands of wire in said 95

recess at the center of said twisting element during the twisting operation, and movable outwardly from said center for releasing said strands of wire subsequent to the twisting operation.

5 11. In a forming machine of the class described, a movably mounted twisting mechanism movable into operative and inoperative position; means for moving said twisting mechanism into operative and inoperative position, said twisting mechanism upon movement to operative position engaging aligned strands of wire; movable dye shoes carried by said twisting mechanism having oppositely disposed faces, each provided with a recess, and movable into position for clamping in said recesses said strands of wire at the center of the twisting mechanism during the twisting operation, and movable upon movement of said twisting mechanism to inoperative position for moving said recesses out of the center of said twisting mechanism and releasing the wire therefrom.

25 12. In a forming machine of the class described, a twisting mechanism comprising a twisting element having a radially disposed slot projecting inwardly from the periphery thereof for the reception of strands of wire to be twisted together; and means movable relatively to said twisting element for, upon movement into one position, clamping tightly against said strands of wire and retaining the same so clamped during the twisting operation and, upon movement to another position, for releasing said strands of wire for permitting free movement outwardly of said slot, of said strands.

35 13. A wire working machine of the character described, comprising a movable carrier; means for moving said carrier; means on said carrier for bending a wire into a loop with the ends of the wire in parallel relationship; wire twisting means on said carrier for twisting the parallel ends of the wire about each other; and means for moving said twisting mechanism into wire engaging position upon the movement of said carrier to a predetermined position.

45 14. A wire working machine of the character described, comprising a movable carrier, means for moving said carrier, means on said carrier for bending a wire into a loop with the ends of the wire in parallel relationship and one end thereof projecting beyond the other, wire twisting means supported by said carrier for twisting the parallel end portions of the wire about each other; means for moving said twisting mechanism into wire engaging position upon a movement of said carrier to a predetermined position, and means for forming a hook on the long end of said wire.

55 15. A wire working machine comprising means for forming wire into a closed loop, and a shank composed of parallel portions of the wire; and twisting means for twisting, subsequent to the formation of the loop, the parallel portions of the

wire which form the shank, said twisting means comprising a member movable transversely of the longitudinal axis of the shank to engage the same.

60 16. A wire working machine comprising a frame, means supported by said frame for bending a wire to form a closed loop portion with the ends thereof in parallel relationship, twisting means for twisting, subsequent to the formation of the loop, the parallel ends of the wire together, said twisting means comprising a twisting member movable transversely of the longitudinal axis of the parallel ends of the wire to engage and disengage the wire, and means for moving said twisting member into engaging and disengaging position.

65 17. A wire working machine comprising a frame, means supported by said frame for bending a wire to form a closed loop portion with the ends of the wire in parallel relationship, twisting means for twisting, subsequent to the formation of the loop, the parallel ends of the wire together, said twisting means comprising a gear provided with a radial slot, means for moving said gear transversely of the parallel ends of the wire to engage the same in said radial slot, and means for rotating said gear.

70 18. A wire working machine comprising means for forming a wire into a loop and a shank portion composed of parallel portions of the wire, twisting means for twisting, subsequent to the formation of the loop, the parallel portions of the wire which form the shank, said twisting means comprising a member movable transversely of the longitudinal axis of the wires forming the shank to engage the same therewith, and means for forming a hook on one end of the wire.

75 19. A wire working machine comprising a frame, means supported by said frame for bending a wire to form a loop portion with the ends of the wire in parallel relationship, twisting means for twisting the parallel ends of the wire together, said twisting means comprising mechanism movable transversely of the longitudinal axis of the parallel ends of the wire to engage and disengage the wire, means for moving said twisting mechanism into engaging and disengaging position, and means for forming a hook on one end of the wire.

80 20. A wire working machine comprising a frame, means supported by said frame for bending a wire to form a loop portion with the ends thereof in parallel relationship, twisting means for twisting the parallel ends of the wire together, said twisting means comprising a gear provided with a radial slot, means for moving said gear transversely of the parallel ends of the wire to engage the wire in said radial slot, means for rotating said gear, and means for forming a hook on one end of the wire.

85 JOHN H. MOORE.
